CIGAR LIGHTER OR SIMILAR ARTICLE

Seymour Rappoport, New York, N. Y., assignor to Ronson Corporation, Newark, N. J., a corporation of New Jersey

Application May 19, 1958, Serial No. 50,969

Term of patent 14 years

(Cl. D48—27)

Fig. 1 is a side elevation of a cigar lighter or similar article embodying my new design;

Fig. 2 is an end elevation thereof;

Fig. 3 is a plan view thereof;

Fig. 4 is a perspective view thereof; and

Fig. 5 is a detail perspective view showing on an enlarged scale as compared to Figs. 1-4 and with the remainder of the structure cut away, the configuration of the grooved portion of the body of the article.

The reverse side of the article as shown in Fig. 1, may be understood as the same in appearance as the side shown in said figure.

I claim:

The ornamental design for a cigar lighter or similar article, substantially as shown and described.
